UNITED STATES PATENT OFFICE.

OTTO S. BEYER, OF EAST RUTHERFORD, NEW JERSEY, ASSIGNOR TO E. W. BLISS COMPANY, A CORPORATION OF WEST VIRGINIA.

SEAMING-MACHINE.

No. 871,856.

Specification of Letters Patent.

Patented Nov. 26, 1907.

Application filed December 26, 1903, Serial No. 186,604.

To all whom it may concern:

Be it known that I, OTTO S. BEYER, a citizen of the United States of America, and a resident of East Rutherford, county of Bergen, and State of New Jersey, have invented 5 certain new and useful Improvements in Seaming-Machines, of which the following is a specification.

My invention relates generally to seaming 10 machines and has more particular reference to the gearing used in driving the different parts of the machine and to the combination of parts and features of construction herein-after set forth.

15 Heretofore, it has been customary to have a plurality of seaming members mounted on the rotating seamer head so as to travel in an orbit around the work to be acted upon, the said seaming members further having a 20 movement toward and away from the work at the proper periods so as to properly engage with or act upon the seam to be formed. In connection with this, it has generally been customary to have an automatic feeding 25 mechanism for the cans adapted to bring the said cans successively into and out of position with regard to the chuck and seaming members, at the moment when the seaming members are in a position to admit the passage 30 of the cans. In some cases, however, it is desirable to have a hand-fed machine and in order that the finished can may be removed by the operator, it is necessary that the movement of the seaming members to- 35 ward and away from the work should cease while the said can is removed and after it is finished. It is obvious that this replacing of the can must be substantially at the moment when the seaming members are in the position 40 farthest away from the work. The seaming members are therefore normally held away from their operating position, and are only actuated at will by the operator.

The seamer head, carrying the seaming 45 member or members can, however, rotate continuously. In carrying out these objects, I provide the seamer head with a pinion for each seaming member which travels around or rotates with the said seamer head and 50 which furthermore has an individual rotation around its own axis which acts to bring the seaming members into operating position. Means are provided for stopping the individual rotation of these pinions at will

and substantially at the moment when the 55 seaming members are farthest away from the work. The parts are so arranged that the said pinion or pinions makes one revolution around its own axis to a certain predetermined number of revolutions of the seamer 60 head. In this instance, the relation is 1 to 12, the pinion making one revolution around its own axis to 12 revolutions of the seamer head. This proportion can of course be changed at will. To impart the necessary 65 motion to this pinion or pinions, I provide a gear placed concentric with the seamer head and running at a speed slightly greater than the said seamer head, the relation being in the present instance $12\frac{1}{5}$ of the said concentric gear to 12 revolutions of the seamer head. This concentric gear is driven from a train of gears which preferably connect with a gear mounted on the spindle of the seamer 70 head and running at the said speed of the 75 seamer head. A clutch mechanism is interposed in the said train of gears suitably controlled to throw the clutch in substantially at the same moment the can is clamped between the work supporter and the chuck. 80 In the present instance, a treadle mechanism is used for this purpose.

A suitable locking means is used to maintain the parts in their working position after they have been moved into the same, and 85 means are provided whereby the said locking means is unlatched or freed automatically so as to disengage the clutch with its co-operating means after a certain predetermined period. In the present instance, the parts are 90 so arranged that after the seamer head has made 12 revolutions and the pinion carried by the same has made one revolution around its own axis that the said clutch mechanism will be thrown out of engagement with its 95 operating mechanism.

The means for stopping the individual rotation of the pinion around its own axis, consists in the present instance of a cam and a stop for preventing the rotation of the said 100 pinion around its own axis beyond one revolution. There is furthermore provided a back stop, so that the parts will not be driven in the other direction, as otherwise would be the case, with the result of driving 105 the gear placed concentric with the seamer head in the opposite direction, as well as the train of gears below the clutch. This back

stop, however, has the effect of preventing the backward rotation of the pinion, the result being that the gear placed concentric with the seamer head and which is rotating 5 at a speed slightly greater than the said seamer head will be carried around at the same speed as the seamer head when the seaming operation ceases. When the clutch is thrown in again, the stop, coöperating with 10 the cam carried by the pinion, will be withdrawn so as to allow the pinion to be rotated around its own axis and the difference in speed between the seamer head and the gear placed concentric with the same being relatively very small, there is no jar or shock in 15 starting or stopping the machine at any time.

In the drawings I have embodied my invention in a useful and preferred form without, however, wishing to be understood as limiting myself in any way to the construction therein set forth.

In the said drawings: Figure 1 is a side elevation of the machine embodying my invention, partly in section. Fig. 2 is a plan view of the under side of the chuck and seamer head showing three seaming members used in the present instance. Fig. 3 is a detail view of the seamer head, showing the 25 cam and stops for the pinion which actuates the seaming members. Fig. 4 is a sectional view on the line $\alpha-\alpha$ of Fig. 1. Fig. 5 is an enlarged detail view, partly in section, of the seamer head and adjacent elements. Fig. 6 is a detail view of the seaming member having 30 two opposed conical deflecting rolls. Fig. 7 is a sectional detail view of the head and seaming members showing more particularly the means for moving the seaming 35 members toward and away from the work. Fig. 8 is a detail view of one of the seaming members as 7 partly in section. Fig. 9 is another detail view of the seaming member 7 showing more particularly the means for 40 moving the conical deflecting rolls toward and away from each other. This view is also partly in section.

Similar characters of reference indicate corresponding parts in the different views. 50 1 indicates a framework of any suitable construction for properly supporting the various parts.

2 indicates the seamer head which is suitably operated from the shaft 3 through the 55 instrumentality of the miter gears 4 and 5.

The seamer head carries one or more seaming members as the case may be, but, is in the present instance provided with three seaming members 6, 7 and 8 which include 60 in part two opposed conical deflecting rolls carried by the member 7. These seaming members may of course be constructed in any suitable way and may be caused to move into and out of seaming position in any 65 suitable manner. Preferably, however, they

are provided with a contour carrier 90 pivoted on the head 2 in the usual manner on the studs 12.

Mounted on the contour carrier is a seaming carrier 13 which in turn carries the seaming tools. This arrangement could of course be reversed and the contour carrier mounted on the seaming carrier, in which instance the seaming tools would be carried by the contour carrier, the only requisite being that the 75 seaming tools partake of the motion of both carriers.

The contour carrier 90 will conveniently take the form of an arm having an extension 91 carrying the roller 9 adapted to travel in 80 the cam 10 carried by the chuck 11. As the seamer head 2 revolves, the seaming members will be carried around with the same and will be caused to travel in an orbit around the work to be acted upon parallel to the 85 contour of the said work. In the present instance, where the work is square, the cam 10 will of course have a contour substantially identical with the contour of the can or work to be acted upon. The cam 10 is of course 90 stationary with the work to be acted upon. The seaming carrier 13 will conveniently take the form of a bell crank lever and is pivoted at 14 on the contour carrier 90. This seaming carrier carries the seaming tools 95 which in the present instance are in the form of rolls, the second member having two opposed conical deflecting rolls. Any suitable means can of course be provided for moving the seaming carrier toward and away from 100 the work. In the present instance, it is constructed as follows: One end of the lever or seaming carrier 13 is connected with the plunger 92 sliding in the cylinder 93 in which is located the spring 94 for yielding to any 105 unevenness in the seam. This tube is carried by a sliding member 95 provided with an expansion spring 96 which normally tends to hold the seaming member away from the work. Inside the contour carrier 90 is a 110 spindle 97 carrying the pinion 16 at its upper end and the cam 15 at its lower end. Carried by the sliding member 95 is a roller 98 with which the cam 15 is adapted to engage to move the seaming carrier toward the work. 115 This construction is common to all three members. The seaming carrier on the first seaming member carries the crimping or curling roll 99, and the seaming carrier on the third seaming member carries the finishing 120 roll 100, while the second seaming member carries two opposed conical deflecting rolls 101 and 102 respectively.

The foregoing describes the construction of the first and third seaming members. The 125 second seaming member, however, must in addition to the above means, be provided with a mechanism for moving the conical deflecting rolls toward and away from each other at the proper moment.

Pivoted on the seaming carrier 13 is a straddling link 103 which carries the lower deflecting roll 102. 104 indicates a stud also mounted on the seaming carrier carrying the 5 lower arm 105 adapted to engage with the straddling link 103. Mounted on the said stud 104 is an upper arm 106 which bears upon a portion of the contour carrier 90. When the seaming carrier moves in toward 10 the work, the arm 106 will engage with the contour carrier 90 thereby causing the arm 105 to move the straddling link 103 and the roll 102 in an upward direction so as to move the said roll 102 up against the conical 15 deflecting roll 101. Upon the return movement of the seaming carrier, the reverse action will take place.

As there are three seaming members in the present instance, there will of course be three 20 pinions, one for each seaming member, but one only will be described. The said pinion 16 of course travels around with the seamer head or rotates with the same. In addition to this, however, it has an individual rotation around its own axis which is imparted to 25 it by means of the gear 17, placed concentric with the seamer head, but rotating at a speed slightly greater than the latter, when driving the pinion. In the present instance, the 30 relation of the parts is such that the seamer head makes 12 revolutions to one individual revolution around its own axis of the pinion, the concentric gear making $12\frac{1}{2}$ revolutions during the same period to impart this one 35 revolution to the said pinion. It will of course be understood that if the concentric gear were driven at the same speed as the seamer head, the pinion would not rotate inasmuch as the said pinion travels in an orbit 40 around with the seamer head and at the same speed as the latter. The said concentric gear 17 receives its motion in a suitable way from a train of gears including the gears 18, 19, 20, and 21. The gears 19 and 20 are 45 mounted on a separate spindle 22, the gear 19 being mounted fast and the gear 20 being mounted loose on the same. The gear 21 moves at the same speed as the seamer head and is mounted upon the spindle 24 which 50 carries the said seamer head. A suitable clutch mechanism is interposed in the said train of gears consisting in this case of the clutch 25 mounted on the spindle 22 and adapted to engage with the gear 20 to cause 55 the motion of the said gear to be imparted to the spindle 22 and thence to the other gears. 26 is the work supporter adapted to receive the can.

27 indicates a treadle, the motion of which 60 is imparted through the rod 28 to the bell crank 29 connected to the loose collar 60 on the work supporter by means of link 61. The work supporter further carries the fixed sleeve 62 between which and the loose sleeve 65 is interposed the spring 63. The bell crank

29 carries an arm 64 which is attached to the link 30 provided with the slot 65 at its free end in which plays the pin 66 of the bell crank 31. Mounted on this pin 66 is a latch 67 provided with a hook 68 engaging the pin 70 70 on the link 30. This latch is further provided with a projection 70 having a slot 71 in which the pin 72, stationary on the framework engages. Connecting with the bell crank 31 is a rod 32 extending upward and 75 mounted on the pin 73 carried by the forked member 35. This member 35 is pivoted on the stud 74 attached to the bracket 75 on the framework, and is provided with two projections 76 and 77 between which extends 80 the arm 78 of the clutch lever 33 engaging in the sleeve 34 of the clutch. This clutch lever 33 is likewise mounted loosely on the stud 74.

Mounted on the pivot 79 of the member 85 35 is a hook 36 which is adapted to engage with the ledge 80 on the bracket 75 to lock the parts when the treadle is depressed. A spring seated plunger 81 tends to push the lower end of the hook 36 outward at all times. Mounted on the pivot 82 of the 90 bracket 75 is a bell crank 43 adapted to move the sleeve 42 downward by means of the lever 44 pivoted on the bell crank 43 and resting on the top of the hook 36. The pinion 16 is provided with the cam 37 with 95 which engages the stop 38 in the notch 39 of the said cam after it has made one revolution around its own axis. This stop releases the cam and thereby the pinion by connections from the sleeve 42 consisting of 100 the rod 41 attached to the said sleeve 42 by means of the screws 84. Rod 41 engages at its lower end a lever 40 which in turn engages with the stop 38. The back stop 45 is also provided to engage with the notch 46 105 of the cam 37 to prevent the pinion from turning backwards as otherwise might be the case.

When it is desired to seam a can, the said 110 can is placed upon the work supporter and the treadle depressed, thereby lifting the work supporter and clamping the can. Through the instrumentality of the link 30, the rod 32 is lifted throwing the clutch 25 in, and lifting the hook 36 up on the ledge 80 at 115 the same time throwing the stop 38 out of engagement with the notch 39 of the cam 37.

Owing to the construction of the link 30 with the slot 65, the can is caused to be clamped slightly in advance of the throwing 120 in of the clutch and the beginning of the seaming operation. The movement of this link 30 causes the latch 67 to turn around the pin 66 by reason of the pin 72 in the slot 71 whereby the hook 68 engages the pin 69 and prevents the parts from returning so long as the hook 36 locks the parts. When the rod is thus elevated, the projection 77 on the member 35 pushes against the arm 78 of the clutch lever 34 moving the clutch in. 130

As the member 35 swings around the pivot 74, the hook 36 is lifted up and the spring seated pin 81 normally pressing the lower end of the hook outward, will cause the said 5 hook to engage properly with the ledge 80 on the bracket locking the parts. The projection 77 is provided with a spring seated plunger 85 so as to take up any discrepancy in the movement of the parts between the clutch 10 25 and hook 36. The throwing out of the stop 38 releases the pinion 16 and the clutch 25 through the train of gears imparts to it an individual rotation around its own axis whereby the seaming members successively 15 move in toward the can and seam the same. After the said pinion 16 has made one revolution, the stop 38 automatically acts through the lever 40, rod 41, sleeve 42, bell crank 43, and lever 44, pushing the hook 36 off the 20 ledge 80, the downward movement of the parts connected thereto being facilitated by means of the spring seated plunger 86 on the bracket 75 acting against a portion of the member 35 so that the release is instantaneous. The member 35 being thus turned 25 around the pivot 74, the projection 76 engages with the arm 78 throwing the clutch 25 out and pressing or pushing the rod 32 downward, thereby causing the work supporter to be released by reason of the latch 30 67 turning around the pin 66 unhooking the hook 68 from engagement with the pin 69 and allowing the link 30 to move back.

The weight of the work supporter will generally be sufficient to cause the return movement when released but the spring 63 also assists in moving it back or down. This release is accomplished substantially at the moment when the seaming members are farthest away from the work. The back stop prevents the rotation of the pinion in the opposite direction as it travels in an orbit around with the seamer head and at the same speed with the same, and the concentric gear 45 from which it receives its motion no longer being driven from its train of gears will rotate at the same speed as the seamer head and in the same direction. If several seaming members are used, each of the said seaming members will be provided with a pinion, but it is only necessary to have a cam, a stop, and back stop on one of the said pinions.

The specific construction of the seaming members is not claimed in this application, 55 as it has been made the subject matter of other applications by me Ser. No. 186,602, filed December 26, 1903 and Ser. No. 186,603, filed December 26, 1903.

Having thus described my invention, what 60 I claim is:

1. In a seaming machine, the combination of a rotating seamer head, one or more seaming members rotating with the seamer head, means for moving said seaming member or 65 members into operating position comprising

in part: a pinion rotating with the seamer head, means for imparting an individual rotation around its own axis to the pinion, and means for stopping the individual rotation of the said pinion without stopping the rotation 70 of the seamer head.

2. In a seaming machine, the combination of a rotating seamer head, one or more seaming members rotating with the seamer head, means for moving said seaming member or 75 members into operating position comprising in part: a pinion rotating with the seamer head, means for imparting an individual rotation around its own axis to the pinion so that the said pinion makes one revolution 80 around its own axis to a predetermined number of revolutions of the seamer head, and means for stopping the individual rotation of the said pinion without stopping the rotation of the seamer head. 85

3. In a seaming machine, the combination of a rotating seamer head, one or more seaming members rotating with the seamer head, means for moving said seaming member or members into operating position comprising 90 in part: a pinion rotating with the seamer head, means for imparting an individual rotation around its own axis to the pinion, and means for stopping the individual rotation of the said pinion substantially at the moment 95 the seaming member or members is or are farthest away from the work.

4. In a seaming machine, the combination of a rotating seamer head, one or more seaming members rotating with the seamer head, 100 means for moving said seaming member or members into operating position comprising in part: a pinion rotating with the seamer head, means for imparting an individual rotation around its own axis to the pinion so 105 that the said pinion makes one revolution around its own axis to a predetermined number of revolutions of the seamer head, and means for stopping the individual rotation of the pinion after it has made one revolution. 110

5. In a seaming machine, the combination of a rotating seamer head, one or more seaming members rotating with the seamer head, means for moving said seaming member or members into operating position comprising 115 in part: a pinion rotating with the seamer head, means for imparting an individual rotation around its own axis to the pinion so that the said pinion makes one revolution around its own axis to a predetermined number of revolutions of the seamer head, and means for stopping the individual rotation of the pinion after it has made one revolution, and substantially at the moment when the seaming member or members is or are far- 120 away from the work. 125

6. In a seaming machine, the combination of a rotating seamer head, one or more seaming members rotating with the seamer head, means for moving said seaming member or 130

members into operating position comprising in part: a pinion rotating with the seamer head, means for imparting an individual rotation around its own axis to the pinion, and 5 means for stopping the individual rotation of the said pinion, without stopping the rotation of the seamer head, substantially at the moment when the seaming member or members is or are farthest away from the work.

10 . 7. In a seaming machine, the combination of a rotating seamer head, one or more seaming members rotating with the seamer head, means for moving said seaming member or members into operating position comprising 15 in part: a pinion rotating with the seamer head, means for imparting an individual rotation around its own axis to the pinion so that the said pinion makes one revolution around its own axis to a predetermined number 20 of revolutions of the seamer head, and means for stopping the individual rotation of the said pinion, without stopping the rotation of the seamer head, substantially at the moment when the seaming member or members is or are farthest away from the work. 25

8. In a seaming machine, the combination of a rotating seamer head, one or more seaming members rotating with the seamer head, means for moving said seaming member or
30 members into operating position comprising in part: a pinion rotating with the seamer head, means for imparting an individual rotation around its own axis to the pinion so that the said pinion makes one revolution
35 around its own axis to a predetermined number of revolutions of the seamer head, and means for stopping the individual rotation of the said pinion without stopping the rotation of the seamer head, after the said pinion has
40 made one revolution.

40 made one revolution.

45 9. In a seaming machine, the combination
of a rotating seamer head, one or more seaming
members rotating with the seamer head,
means for moving said seaming member or
members into operating position comprising
in part: a pinion rotating with the seamer
head, means for imparting an individual ro-
tation around its own axis to the pinion so
that the said pinion makes one revolution
50 around its own axis to a predetermined num-
ber of revolutions of the seamer head, and
means for stopping the individual rotation of
the said pinion without stopping the rotation
of the seamer head after the said pinion has
55 made one revolution and substantially at the
moment when the seaming member or mem-
bers is or are farthest away from the work.

10. In a seaming machine, the combination of a rotating seamer head, one or more
60 seaming members rotating with the seamer head, means for moving said seaming member or members into operating position comprising in part: a pinion rotating with the seamer head, a gear concentric with the
65 seamer head for imparting an individual ro-

tation around its own axis to the said pinion, a train of gears for operating the said concentric gear, a clutch interposed in the said train of gears, means for throwing the clutch out and for stopping the individual rotation of the gear, and means for preventing the pinion from turning in the opposite direction. 70

11. In a seaming machine, the combination of a rotating seamer head, one or more 75 seaming members rotating with the seamer head, means for moving said seaming member or members into operating position comprising in part: a pinion rotating with the seamer head, a gear concentric with the 80 seamer head for imparting an individual rotation around its own axis to the pinion so that the said pinion makes one revolution around its own axis to a predetermined number of revolutions of the seamer head, a train 85 of gears for operating the said concentric gear, a clutch interposed in the said train of gears, means for throwing the clutch out and for stopping the individual rotation of the gear, and means for preventing the pinion 90 from turning in the opposite direction.

12. In a seaming machine, the combination of a rotating seamer head, one or more seaming members rotating with the seamer head, means for moving said seaming member or members into operating position comprising in part: a pinion rotating with the seamer head, a gear concentric with the seamer head for imparting an individual rotation around its own axis to the said pinion, a train of gears for operating said concentric gear, a clutch interposed in the said train of gears, means for throwing the clutch out and for stopping the individual rotation of the pinion substantially at the moment the seaming member or members is or are farthest away from the work, and means for preventing the pinion from turning in the opposite direction. 95 100 105

13. In a seaming machine, the combination of a rotating seamer head, one or more seaming members rotating with the seamer head, means for moving said seaming member or members into operating position comprising in part: a pinion rotating with the seamer head, a gear concentric with the seamer head for imparting an individual rotation around its own axis to the pinion so that the said pinion makes one revolution around its own axis to a predetermined number of revolutions of the seamer head, a train of gears for operating said concentric gear, a clutch interposed in the said train of gears, means for throwing the clutch out and for stopping the individual rotation of the pinion, and means for preventing the pinion from turning in the opposite direction. 110 115 120 125

14. In a seaming machine, the combination of a rotating seamer head, one or more seaming members rotating with the seamer 130

head, means for moving said seaming member or members into operating position comprising in part: a pinion rotating with the seamer head, a gear concentric with the 5 seamer head, for imparting an individual rotation around its own axis to the pinion so that the said pinion makes one revolution around its own axis to a predetermined number of revolutions of the seamer head, a train 10 of gears for operating the said concentric gear, a clutch interposed in the said train of gears, means for throwing the clutch out and for stopping the individual rotation of the pinion after it has made one revolution and 15 substantially at the moment when the seaming member or members is or are farthest away from the work, and means for preventing the pinion from turning in the opposite direction.

20 15. In a seaming machine, the combination of a rotating seamer head, one or more seaming members rotating with the seamer head, means for moving said seaming member or members into operating position comprising in part: a pinion rotating with the 25 seamer head, a gear concentric with the seamer head running at a speed somewhat greater than the said seamer head for imparting an individual rotation around its own 30 axis to the pinion, a train of gears for operating the said concentric gear, a clutch interposed in the said train of gears, means for throwing the clutch out and for stopping the individual rotation of the pinion and means 35 for preventing the pinion from turning in the opposite direction whereby the said pinion will cause the concentric gear to rotate at the same speed as the seamer head and in the same direction.

40 16. In a seaming machine, the combination of a rotating seamer head, one or more seaming members rotating with the seamer head, means for moving said seaming member or members into operating position comprising in part: a pinion rotating with the 45 seamer head, a gear concentric with the seamer head rotating at a speed somewhat greater than the said seamer head for imparting an individual rotation around its own 50 axis to the pinion so that the said pinion makes one revolution around its own axis to a predetermined number of revolutions of the seamer head, a train of gears for operating the said concentric gear, a clutch interposed 55 in the said train of gears, means for throwing the clutch out and for stopping the individual rotation of the pinion, means for preventing the pinion from turning in the opposite direction whereby the said pinion will cause the 60 concentric gear to rotate at the same speed as the seamer head and in the same direction.

17. In a seaming machine, the combination of a rotating seamer head, one or more seaming members rotating with the seamer

head, means for moving said seaming member or members into operating position comprising in part: a pinion rotating with the seamer head, a gear concentric with the seamer head running at a speed somewhat greater than the said seamer head for imparting an individual rotation around its own axis to the pinion, a train of gears for operating the said concentric gear, a clutch interposed in the said train of gears, means for throwing the clutch out and for stopping the individual rotation of the pinion substantially at the moment the seaming member or members is or are farthest away from the work, means for preventing the pinion from turning in the opposite direction whereby the said pinion will cause the concentric gear to rotate at the same speed as the seamer head and in the same direction.

18. In a seaming machine, the combination of a rotating seamer head, one or more seaming members rotating with the seamer head, means for moving said seaming member or members into operating position comprising in part: a pinion rotating with the seamer head, a gear concentric with the seamer head running at a speed somewhat greater than the said seamer head for imparting an individual rotation around its own axis to the pinion so that the said pinion makes one revolution around its own axis to a predetermined number of revolutions of the seamer head, a train of gears for operating the said concentric gear, a clutch interposed in the said train of gears, means for throwing the clutch out and for stopping the individual rotation of the pinion after it has made one revolution, and means for preventing the pinion from turning in the opposite direction whereby the said pinion will cause the concentric gear to rotate at the same speed as the seamer head and in the same direction.

19. In a seaming machine, the combination of a rotating seamer head, one or more seaming members rotating with the seamer head, means for moving said seaming member or members into operating position comprising in part: a pinion rotating with the seamer head, a gear concentric with the seamer head running at a speed somewhat greater than that of the seamer head, for imparting an individual rotation around its own axis to the pinion so that the said pinion makes one revolution around its own axis to a predetermined number of revolutions of the seamer head, a train of gears for operating said concentric gear, a clutch interposed in the said train of gears, means for throwing the clutch out and for stopping the individual rotation of the pinion after it has made one revolution and substantially at the moment when the seaming member or members is or are farthest away from the work and means for preventing the pinion from turn-

ing in the opposite direction whereby the said pinion will cause the concentric gear to rotate at the same speed as the seamer head and in the same direction.

5 20. In a seaming machine, the combination of a rotating seamer head, one or more seaming members rotating with the seamer head, means for moving said seaming member or members into operating position comprising in part: a pinion rotating with the seamer head, a gear concentric with the seamer head for imparting an individual rotation around its own axis to the pinion, a train of gears for operating said concentric 10 gear, a clutch interposed in the said train of gears, a work supporter, a chuck, a treadle mechanism for raising the work supporter so as to clamp the can between the chuck and the work supporter and for throwing the 15 clutch in, means for throwing the clutch out and for releasing the can thereby stopping the individual rotation of the pinion, and means for preventing the pinion from turning 20 in the opposite direction.

25 21. In a seaming machine, the combination of a rotating seamer head, one or more seaming members rotating with the seamer head, means for moving said seaming member or members into operating position comprising in part: a pinion rotating with the seamer head, a gear concentric with the seamer head for imparting an individual rotation around its own axis to the pinion, so that the said pinion makes one revolution 30 around its own axis to a predetermined number of revolutions of the seamer head, a train of gears for operating said concentric gear, a clutch interposed in the said train of gears, a work supporter, a chuck, a treadle mechanism 35 for raising the work supporter so as to clamp the can between the chuck and the work supporter and for throwing the clutch in, means for throwing the clutch out and for releasing the can thereby stopping the individual rotation of the pinion, and means for 40 preventing the pinion from turning in the opposite direction.

22. In a seaming machine, the combination of a rotating seamer head, one or more seaming members rotating with the seamer head, means for moving said seaming member or members into operating position comprising in part: a pinion rotating with the seamer head, a gear concentric with the seamer head for imparting an individual rotation around its own axis to the pinion, a train of gears for operating said concentric gear, a clutch interposed in the said train of gears, a work supporter, a chuck, a treadle mechanism for raising the work supporter so as to clamp the can between the chuck and the work supporter and for throwing the clutch in, means for throwing the clutch out and for releasing the can thereby stopping

the individual rotation of the pinion substantially at the moment the seaming member or members is or are farthest away from the work. 65

23. In a seaming machine, the combination of a rotating seamer head, one or more seaming members rotating with the seamer head, means for moving said seaming member or members into operating position comprising in part: a pinion rotating with the seamer head, a gear concentric with the seamer head for imparting an individual rotation around its own axis to the pinion, so that the said pinion makes one revolution around its own axis to a predetermined number of revolutions of the seamer head, a train of gears for operating said concentric gear, a clutch interposed in the said train of gears, a work supporter, a chuck, a treadle mechanism for raising the work supporter so as to clamp the can between the chuck and the work supporter and for throwing the clutch in, means for throwing the clutch out and for releasing the can thereby stopping the individual rotation of the pinion after it has made one revolution, and means for preventing the pinion from turning in the opposite direction. 70 75 80 85 90

24. In a seaming machine, the combination of a rotating seamer head, one or more seaming members rotating with the seamer head, means for moving said seaming member or members into operating position comprising in part: a pinion rotating with the seamer head, a gear concentric with the seamer head for imparting an individual rotation around its own axis to the pinion so that the said pinion makes one revolution around its own axis to a predetermined number of revolutions of the seamer head, a train of gears for operating said concentric gear, a clutch interposed in the said train of gears, a work supporter, a chuck, a treadle mechanism for raising the work supporter so as to clamp the can between the chuck and the work supporter and for throwing the clutch in, means for throwing the clutch out and for releasing the can thereby stopping the individual rotation of the pinion, after it has made one revolution and substantially at the moment when the seaming member or members is or are farthest away from the work, and means for preventing the pinion from turning in the opposite direction. 95 100 105 110 115

25. In a seaming machine, the combination of a rotating seamer head, one or more seaming members rotating with the seamer head, means for moving said seaming member or members into operating position comprising in part: a pinion rotating with the seamer head, a gear concentric with the seamer head running at a speed somewhat greater than the said seamer head, for imparting an individual rotation around its own

axis to the pinion, a train of gears for operating said concentric gear, a clutch interposed in the said train of gears, a work supporter, a chuck, a treadle mechanism for 5 raising the work supporter so as to clamp the can between the chuck and the work supporter and for throwing the clutch in, means for throwing the clutch out and for releasing the can thereby stopping the individual rotation of the pinion, and means for preventing the pinion from turning in the opposite direction, whereby the said pinion will cause the concentric gear to rotate at the same speed as the seamer head and in the same 10 direction.

26. In a seaming machine, the combination of a rotating seamer head, one or more seaming members rotating with the seamer head, means for moving said seaming member or members into operating position comprising in part: a pinion rotating with the seamer head, a gear concentric with the seamer head running at a speed somewhat greater than the said seamer head for imparting an individual rotation around its own axis to the pinion, a train of gears for operating said concentric gear, a clutch interposed in the said train of gears, a work supporter, a chuck, a treadle mechanism for 20 raising the work supporter so as to clamp the can between the chuck and the work supporter and for throwing the clutch in, means for throwing the clutch out and for releasing the can thereby stopping the individual rotation of the pinion substantially at the moment the seaming member or members is or are farthest away from the work, whereby the said pinion will cause the concentric gear to rotate at the same speed as the seamer head 30 and in the same direction.

27. In a seaming machine, the combination of a rotating seamer head, one or more seaming members rotating with the seamer head, means for moving said seaming member or members into operating position comprising in part: a pinion rotating with the seamer head, a gear concentric with the seamer head running at a speed somewhat greater than the said seamer head for imparting an individual rotation around its own axis to the pinion, so that the said pinion makes one revolution around its own axis to a predetermined number of revolutions of the seamer head, a train of gears for operating said concentric gear, a clutch interposed in the said train of gears, a work supporter, a chuck, a treadle mechanism for raising the work supporter so as to clamp the can between the chuck and the work supporter and for throwing the clutch in, means for throwing the clutch out and for releasing the can thereby stopping the individual rotation of the pinion, and means for preventing the pinion from turning in the opposite direction, whereby the said pinion will cause

the concentric gear to rotate at the same speed as the seamer head and in the same direction.

28. In a seaming machine, the combination of a rotating seamer head, one or more seaming members rotating with the seamer head, means for moving said seaming member or members into operating position comprising in part: a pinion rotating with the seamer head, a gear concentric with the seamer head running at a speed somewhat greater than the said seamer head, for imparting an individual rotation around its own axis to the pinion, so that the said pinion makes one revolution around its own axis to a predetermined number of revolutions of the seamer head, a train of gears for operating said concentric gear, a clutch interposed in the said train of gears, a work supporter, a chuck, a treadle mechanism for 70 raising the work supporter so as to clamp the can between the chuck and the work supporter and for throwing the clutch in, means for throwing the clutch out and for releasing the can thereby stopping the individual rotation of the pinion after it has made one revolution, and means for preventing the pinion from turning in the opposite direction whereby the said pinion will cause the concentric gear to rotate at the same speed as the seamer head and in the same direction.

29. In a seaming machine, the combination of a rotating seamer head, one or more seaming members rotating with the seamer head, means for moving said seaming member or members into operating position comprising in part: a pinion rotating with the seamer head, a gear concentric with the seamer head running at a speed somewhat greater than the said seamer head, for imparting an individual rotation around its own axis to the pinion so that the said pinion makes one revolution around its own axis to a predetermined number of revolutions of the seamer head, a train of gears for operating said concentric gear, a clutch interposed in the said train of gears, a work supporter, a chuck, a treadle mechanism for raising the work supporter so as to clamp the can between the chuck and the work supporter and for throwing the clutch in, means for throwing the clutch out and for releasing the can thereby stopping the individual rotation of the pinion, after it has made one revolution and substantially at the moment when the seaming member or members is or are farthest away from the work, and means for preventing the pinion from turning in the opposite direction whereby the said pinion will cause the concentric gear to rotate at the same speed as the seamer head and in the same direction.

30. In a seaming machine, the combination of a rotating seamer head, a pinion ro-

tating with the same, a gear concentric with the seamer head for imparting an individual rotation around its own axis to the pinion, a cam moving with the pinion, a stop engaging with the said cam to stop the individual rotation of the pinion after it has made one revolution around its own axis, and a back stop for preventing the pinion from turning in the opposite direction.

31. In a seaming machine, the combination of a rotating seamer head, a pinion rotating with the same, a gear concentric with the seamer head for imparting an individual rotation around its own axis to the pinion, a cam moving with the pinion, a stop engaging with the said cam to stop the individual rotation of the pinion after it has made one revolution around its own axis, and a back stop for preventing the pinion from turning in the opposite direction, a train of gears for imparting motion to the said concentric gear, a clutch interposed in said train of gears, and means operated simultaneously with the stepping of the pinion for throwing out the clutch.

32. In a seaming machine, the combination with a constantly rotating seamer head, of a plurality of seaming members carried by the said head, a train of gears for causing the seaming members to move toward and away from the work, a clutch interposed in said train of gears, means for throwing the clutch in, and means for automatically releasing the clutch after the seaming operation is finished.

33. In a seaming machine, the combination with a constantly rotating seamer head, of a plurality of seaming members carried by the said head, a train of gears for causing the seaming members to move toward and away from the work, a clutch interposed in said train of gears, means for throwing the clutch in, and means for automatically releasing the clutch after the seaming operation is finished and substantially at the moment the seaming members are farthest away from the work.

34. In a seaming machine, the combination with a constantly rotating seamer head, of a plurality of seaming members carried by the said head, a clamp, and a work supporter, a train of gears for causing the seaming members to move toward and away from the work, a clutch interposed in the said train of gears, means for raising the work supporter to clamp the can and for throwing the clutch

in, and means for automatically releasing the clutch and the work supporter after the seaming operation is finished.

35. In a seaming machine, the combination with a constantly rotating seamer head, of a plurality of seaming members carried by the said head, a clamp, and a work supporter, a train of gears for causing the seaming members to move toward and away from the work, a clutch interposed in the said train of gears, means for raising the work supporter to clamp the can and for throwing the clutch in, and means for automatically releasing the clutch and the work supporter after the seaming operation is finished, and substantially at the moment the seaming members are farthest away from the work.

36. In a seaming machine, the combination with a constantly rotating seamer head, of a plurality of seaming members carried by the said head, a clamp, and a work supporter, a train of gears for causing the seaming members to move toward and away from the work, a clutch interposed in the said train of gears for raising the work supporter to clamp the can and for throwing the clutch in, a locking mechanism for locking the parts in this position operated when the clutch is thrown in, and means for automatically releasing the locking mechanism, the clutch and the work supporter after the seaming operation is finished.

37. In a seaming machine, the combination with a constantly rotating seamer head, of a plurality of seaming members carried by the said head, a clamp, and a work supporter, a train of gears for causing the seaming members to move toward and away from the work, a clutch interposed in the said train of gears for raising the work supporter to clamp the can and for throwing the clutch in, a locking mechanism for locking the parts in this position operated when the clutch is thrown in, and means for automatically releasing the locking mechanism, the clutch and the work supporter after the seaming operation is finished and substantially at the moment the seaming members are farthest away from the work.

Signed at New York, N. Y. this 12th day of December 1903.
